UNITED STATES PATENT OFFICE.

HENRY EGGERS, OF DENVER, COLORADO.

ORE-PULVERIZING BALL-MILL.

1,235,449.

Specification of Letters Patent. Patented July 31, 1917.

Application filed February 24, 1917. Serial No. 150,790.

To all whom it may concern:

Be it known that I, HENRY EGGERS, a citizen of the United States of America, residing at the city and county of Denver and State of Colorado, have invented a new and useful Ore-Pulverizing Ball-Mill, of which the following is a specification:

My invention relates to improvements in screening element for rotary ore-grinding ball mills; and the objects of my invention are:

First. To provide an ore-grinding ball mill that is provided with a mobile screening element.

Second. To provide an ore-grinding ball mill that is provided with a constantly shifting screening element.

Third. To provide an ore-grinding ball mill that is provided with a screening element that cannot clog up and that may assist in further pulverizing the ore in the mill that is not pulverized fine enough by the regular ore grinding large ball compartment of the mill to enter this screening element.

I attain these objects by the mechanism illustrated in the accompany drawings, in which:

Figure 1, is a side elevation of the improved ore grinding ball mill.

Fig. 2, is an end view of Fig. 1.

Fig. 3, is a vertical, longitudinal, sectional view of the same.

Fig. 4, is a front view of one of the partition plates.

Fig. 5, is a transverse, sectional view on the line 5—5 of Fig. 3.

Fig. 6, is a front view of a modified form of the partitions, showing the same made in sections.

Fig. 7, is a detail sectional view showing a modification of the combined trunnion and ore inlet. And

Fig. 8, is a sectional view of a modified form of the lining at the discharge end of the mill.

Similar letters of reference refer to similar parts throughout the several views.

Referring to the accompanying drawings:

The numeral 1 indicates the ore-feeding section of the improved ore grinding ball mill; 2, the ore-grinding section, and 3, the ore screening and discharging hood or section. The sections 2 and 3 have registering flanges 4 and 5, respectively, which are

secured together by bolts 6. The section 2 is also provided with a flange 7, which registers with and is bolted to the end plate or section 1, by bolts 8, the flange 7 being of slightly greater diameter than the plate 1, for a purpose to be hereinafter explained. The improved mill then comprises three sections, as shown by Fig. 3, which enable the mill to be conveniently assembled and taken down, and which permit of the most convenient manner of inserting and securing the screens and lining member as will be explained hereinafter.

The sections 1 and 3 are provided with relatively large hollow trunnions 9 and 10 respectively, which are mounted in bearing blocks or standards 11 and 12 respectively, which are bolted to metal supporting plates 13 and 14 respectively, which preferably rest upon and are suitably secured to concrete piers or foundations 15.

Thus the center section has a flange at each end which joins the flanges on the inner ends of the end sections, and the flanges are all bolted together as above mentioned, the end surfaces of the flanged ends of the sections being machined to make close fitting joints between them.

The trunnions 9 and 10 are both hollow, and the ore is fed into the trunnion 9 by means of a rotary scoop 16, of a type in common use, which is bolted to a flange 17 on the end of the said trunnion 9.

The rear end of the section 2 of the mill, is formed with an introverted annular flange 16, and before the sections 1 and 2 are bolted together, a hardened steel lining 17 is placed in the section 2, its rear end abutting against the annular flange 16. This lining is slightly shorter than the section 2, and a hardened steel end plate 18 is inserted in the forward end of the said section and rests against the forward end of the lining, as shown by Fig. 3, and this plate has an axial opening of the same diameter as the ore feed inlet in the trunnion 9. The plate 18 is held in place by the section 1, when the said section is bolted to the section 2.

Within the section 3 is placed a partition 19 similar to that shown in Fig. 4, and which is circular in form and of a diameter to fit snugly within the section 3. This partition abuts against the outer end of the annular flange 16, and is preferably in the form of a single or unitary member comprising an outer ring or rim portion and a

central body portion 20, that part of the plate lying between the rim and the body portion being so slotted as preferably to form a series of concentric hexagons, the 5 ends of the bars formed by these slots being integrally connected to radial bars, which extend from the body portion to the rim. While the partition is preferably of unitary form, as shown by Fig. 4, it may also be 10 made in sections, as shown in Fig. 6, in which figure the partition is formed of three sections, such arrangement affording greater convenience in handling and shipping.

Opposite to the partition 19 and within 15 the hood section 3, which is the discharge section of the mill, I place another partition 21, which is also in the form of a single piece disk, but which may also be made in sections, if desired. Each of these partitions 20 is provided with lateral lugs 22 and 23 respectively, that are positioned opposite each other on their adjoining sides and bear against each other and thus hold the said partitions apart. The partition 21 is held 25 up against the partition 19 by wedges 24, that lie between the inner inclined surface of the section 3, and the partition 23. These wedges are supported and operated by bolts 25, which extend through them and through 30 the peripheral surface of the section 3. The screen partition 21 has an axial projection 2^a, which extends to the entrance of the hollow outlet trunnion 10, and is provided with grooves as shown at 2^b, which catch the 35 product passing out through the partition 21, and direct it into the outlet trunnion, as will be understood by reference to Fig. 3.

These partitions are preferably placed about two inches apart, although if desired 40 they may be placed farther apart. Each bolt 25 carries a nut on its outer end, as shown in Fig. 5, and when the nuts are turned, the bolts are drawn upon, and the wedges 24 jam the partition 21 against the 45 partition 19, which latter partition is thereby jammed against the annular flange 16 of the section 2 of the mill, and thus the two partitions are held rigidly within the section 3, so as to rotate with the mill, the 50 lugs 22 and 23 defining the space between the said partitions.

Between these partitions 19 and 21, I place a body of relatively small balls, that is, balls that are small in comparison with 55 the balls that are used in the regular ore grinding compartment of the mill, the balls in the regular grinding compartment being from about one and a half to five inches in diameter, while those used in the screening 60 compartment between the two partitions are preferably about one-quarter to three-eighths of an inch in diameter. The screening apertures or narrow oblong slots in the partitions permit the ground ore to pass 65 freely through them, while the interstices

between the small balls represent the screen openings, and the thicker the mass of balls the air is obliged to pass through, the smaller will be the particle that is able to pass; hence the size of ball as well as the thickness of the layer will determine the 70 mesh product that will issue from the mill.

The screening apertures or slots in the partitions preferably taper or are widest 75 at their ends that discharge into the small ball screening element, and smallest on the large ball ore grinding compartment side of the casing.

The space between the two partitions constitutes the screening compartment, and the 80 small balls that are placed in the compartment constitute the screening element.

Any suitable means may be employed to rotate the improved ball mill, but this is 85 preferably accomplished in the following manner: to the flange 7 of the section 2 of the mill, is secured a ring form of gear wheel 26, by bolts 27. This gear wheel meshes with a pinion 28, on a shaft 29, which is mounted in bearings 30 and 31, 90 which are bolted to the supporting bars 13 and 14 respectively on the pins 15. The end of the shaft 29 opposite to that which carries the pinion 28 has rigidly mounted thereon a pulley 32, which may be connected by a belt 95 with a power source.

My invention contemplates broadly the use of any arrangement by which a mobile body of balls, pieces of metal, hard pebbles or other ore grinding material is confined 100 in a compartment separate from the main ore grinding compartment by a suitable ground-ore passing partition, and also separated from the screened ore discharging outlet in the trunnion.

The small ore screening balls which lie 105 between the partitions 19 and 21, are preferably inserted into their compartment through apertures that are closed by threaded plugs 33, and that are preferably positioned in the circumferential wall of the casing between the two partitions, in positions to be easily opened and closed to permit the removal of worn balls and the insertion of new ones, when desired.

In Fig. 3, the bore of the trunnion 9 through which the ore is fed to the mill, is shown smooth, but if desired the said bore may be formed with a spiral channel or groove, which will act to positively carry 120 the ore forward into the mill, as it feeds into the bore from the scoop 16.

In Fig. 7 is shown a modified form of feed trunnion 34, which is provided with a spiral channel 35.

The trunnion 10 of the mill is provided with a tapered, removable outlet sleeve or lining 36, which if desired may be formed with a spiral channel 37, as shown by Fig. 8, and the outer end of the trunnion is pro- 130

vided with a flared removable rim 38, which discharges the product clear of the bearing 12, and thus prevents the product from working into the said bearing.

5 The operation of my improved mobile screening ball ore grinding mill is as follows:

Having started the mill to running at a proper speed, the ore, which is first broken up in rock breakers, is fed from the scoop 16 into the mill, and is subjected to the grinding action of the large balls therein, which, with the small screening balls in the screening compartment of the mill, are 15 continuously rolling over and over as the mill rotates.

This continued rotating action of the mill keeps the large and small balls rolling over and over each other, and in the main grinding compartment of the mill the ore is 20 ground to a powder. This ground powdered ore in the main compartment of the mill gradually feeds through the slots in the partition 19, into the screening compartment 25 containing the small balls, which is the final screen of the mill, and the ore in order to pass through these small balls will have been reduced to the desired mesh.

The mobile screening compartment of the mill operates to thoroughly screen the ore, and at the same time keep it constantly moving, and moreover, acts to regrind it to a more even product, which is a matter of value and an advantage where an evenly 35 ground product is required, as in flotation and cyanid processes, and in particular the body of small balls as the mill rotates roll over and over each other through the mass of ore and keep the whole mass moving 40 among the body of balls, and the reground thoroughly screened product as it works through them, enters the slots of the second partition and passes through them and discharges through the trunnion at the discharge end of the mill.

And while I have illustrated the preferred construction and arrangement of my mill, I do not wish to be limited to it, as many changes might be made without departing 50 from the spirit of my invention.

Having described my invention, what I claim as new and desire to secure by Letters Patent, is:

1. In an ore pulverizing ball mill of the 55 character described, a horizontal cylindrical rotatable ball-holding casing having an inverted annular flange at one end, a suitable metal lining in said casing which abuts at one end against said annular flange, a 60 wear plate in the opposite end of said casing which abuts against the adjacent end of said lining, a cap secured to the end of said casing adjoining said plate having a hollow axial trunnion which forms the inlet to said 65 casing, said wear plate having an aperture

registering with said inlet, a hood bolted to the opposite end of the casing having an axial trunnion which forms an outlet, a pair of spaced screen partitions in said hood, the inner one abutting against said annular 70 flange, and means carried by the hood for jamming the outer screen against the inner screen and thereby jamming the inner screen against said flange, the space between said screens being for the reception of small 75 hard metal balls, bearings for said trunnions and means for rotating said mill.

2. An ore pulverizing ball mill of the character described, comprising a ball-holding chamber having an annular abutment 80 at one end, a hood section secured to the abutment end of the casing having an axial outlet in the form of a trunnion, a cap on the opposite end of the casing having an inlet in the form of a hollow trunnion and 85 bearings for said trunnions, a pair of spaced screen partitions in said hood section and abutting lugs on said partitions for defining the space between them, the inner partition bearing against the annular abutment on 90 said casing, radially disposed wedges interposed between the outer partition and the end wall of the hood, the said wall being slightly dished as shown, and bolts extending through said wedges and through the peripheral wall of the hood and provided with nuts on their outer ends, the space between the partitions being for the reception of 95 small hard metal balls, and means for rotating the casing.

3. In an ore pulverizing ball mill of the character described, the combination with a lined horizontally disposed ball-holding grinding casing having a hollow trunnion, of a hood section bolted to the opposite end 105 of the casing, having a hollow trunnion, bearings for said trunnions, and means for rotating said mill, a pair of spaced screen partitions in said hood, the outer partition having a grooved projection extending to 110 the entrance of the adjacent hollow trunnion, the space between said partitions being for the reception of small hard metal balls, and means for rotating said mill.

4. In an ore pulverizing ball mill of the 115 character described, the combination with a ball-holding grinding chamber having an inlet, of a hood secured to one end of said chamber having an outlet, a pair of spaced partitions in said hood, each having a plurality 120 of concentrically arranged slots extending through them, the space between said partitions being partially filled with small hard metal balls, threaded apertures being formed in said hood coinciding with the space between said partitions, threaded plugs in said apertures, and means for rotating said mill.

5. In an ore pulverizing ball mill, the combination with a ball-holding grinding chamber having an inlet at one end and an 130

introverted flange at the other end, of a hood secured to the latter end of said chamber, having an outlet, a pair of spaced partitions in said hood, one of which abuts against the said introverted flange, each of said partitions having a plurality of concentrically arranged slots extending through them, means connected with the hood for clamping said partitions against said flange, the space between said partitions being for the reception of small hard metal balls, said

hood being provided with plugged ball-admitting apertures coinciding with the space between said partitions, and means for rotating said mill.

15

In testimony whereof I affix my signature in presence of two witnesses.

HENRY EGGERS.
